COMBINATION TRUNK

Filed Feb. 9, 1925

UNITED STATES PATENT OFFICE.

EVA Z. HURSH, OF DETROIT, MICHIGAN.

COMBINATION TRUNK.

Application filed February 9, 1925. Serial No. 7,844.

My invention relates to a new and useful improvement in a combination trunk and has for its object the provision of a trunk provided with a plurality of drawers and a slideable drawer forming member adapted for use as a writing desk.

Another object of the invention is the provision in the combination trunk of the desk forming member so constructed and arranged 10 as to be quickly and easily moved to operative position and also rigidly secured and quickly and easily moved to inoperative position so as to require a minimum amount of space.

Other objects will appear hereinafter.

15 The invention consists in the combination and arrangement of parts hereinafter described and claimed.

The invention will be best understood by reference to the accompanying drawings 20 which form a part of this specification and in which,

Fig. 1 is a perspective view of the invention showing the trunk in open position.

Fig. 2 is a fragmentary view showing the 25 desk forming member in said elevation.

Fig. 3 is a perspective view of the modified form of the desk forming member.

As illustrated in the drawings the invention as shown applies to a trunk although the 30 invention could also be utilized in connection with a suitcase or similar receptacle. As shown in the drawings the trunk comprises a main body 7 having a cover 8 hingedly connected thereto, the trunk being of the type 35 commonly known as a wardrobe trunk. A plurality of drawers 9 are positioned for slideable movement in the main body 7. Slidably mounted in the main body 7 is a comparatively shallow drawer forming member 40 having the front wall 10 hingedly mounted and adapted for swinging downwardly as shown in Fig. 1 to permit the base 11 of the drawer to be used as a writing desk or surface, partitions 12 and 13 being mounted at 45 the rear end of the base 11 to provide, with the cover portion 14, pigeon-holes for containing stationery and the like. When the front wall 10 is raised to operative position it is locked by a suitable latch 15 which 50 is mounted on the inner side of the side walls 16 and 17. Swingingly mounted on the upper surface of each of the side walls 16 and 17 is a supporting arm 18 adapted for engaging a hook 19 mounted in the side walls of the 55 main body 7 of the trunk. As shown in Fig-

ure 2 the side walls are recessed at 20 to provide a space for accommodating the hooks 19 so that same will not prevent the closing of the cover 8 upon the main body 7. These arms 18 are provided with eyelets 21 which engage in eyescrews 22. These eyescrews are also positioned in recesses 23 formed in the side walls 16 and 17. When in an operative position these arms may be swung downwardly to lie in the drawer shown in Fig. 1. When the 60 drawer is pulled out into the position shown in Fig. 1 and the arms engaged in the hooks 19 the base 11 is held in rigid position so that a firm writing desk or table is provided.

In the form shown in Fig. 3 I have provided the drawer forming member with a cover 24 which is provided with a suitable latch 25 adapted to engage the front wall 10. The cover 24 is used as the writing desk or surface and the drawer proper used for 70 containing various articles. The supporting arms 18 are similarly mounted for engaging hooks such as already described. When the arms 18 are not in use the same may be placed in an engagement with the cover 24 suitable 75 grooves 26 being provided for accommodating these arms.

The use of such a device for a writing desk is particularly desirable by those occupying 80 rooms in which the space is limited and in which no table is provided. The writing desk thus provided in the trunk is convenient for use and durable of structure so that the utility of the trunk is considerably increased.

While I have illustrated and described the 90 preferred form of structure, I do not wish to limit myself to the precise form of structure shown, but desire to avail myself of such variations and modifications as come within the scope of the appended claims.

Having thus described my invention, what I claim as new and desire to secure by Letters Patent is:

1. In combination with a trunk having a plurality of drawers therein, a comparatively 100 shallow drawer forming member having side walls and a front wall, said front wall being swingably mounted on said member and adapted for swinging into a downwardly extending position for permitting the use of the base of said drawer as a writing surface; and means permanently connected swingably at one end to said drawer forming member and adapted for detachable connection at the other end to said trunk for bracing said 105 110

drawer forming member when used as a desk and preventing inward movement of the same.

2. In combination with a trunk, a shallow drawer forming member slidably mounted thereon and adapted for being extended outwardly therefrom; side walls and a front wall on said drawer forming member, said front wall being swingably mounted and adapted 5 for movement into depending position from the base of said drawer forming member to permit use of said base as a desk, said drawer

10 forming member fitting snugly in said trunk; and means permanently attached at one end swingably on the upper edges of said side walls and detachably engaging said trunk for retaining said drawer forming portion in outwardly directed position, said means being non-interfering when moved to inoperative position with slidable movement of said drawer in said trunk. 15

In testimony whereof I have signed the foregoing specification.

EVA Z. HURSH.
